UNITED STATES PATENT OFFICE.

PETER E. KROEHLER, OF NAPERVILLE, ILLINOIS.

TABLE-BED.

1,216,704.

Specification of Letters Patent. Patented Feb. 20, 1917.

Original application filed October 18, 1913, Serial No. 795,875. Divided and this application filed January 31, 1914. Serial No. 815,750.

To all whom it may concern:

Be it known that I, PETER E. KROEHLER, a citizen of the United States, residing at Naperville, in the county of DuPage and 5 State of Illinois, have invented a new and useful Improvement in Table-Beds, of which the following is a specification.

The present invention constitutes an improvement upon the table-bed disclosed in 10 my application No. 795,875, filed October 18, 1913.

My primary object is to provide an improved table-bed of simplified construction and improved operation, which shall be durable, readily convertible, and which shall 15 present a pleasing appearance.

The invention is illustrated in its preferred embodiment in the accompanying drawings, in which—

20 Figure 1 represents an elevational view of a table-bed constructed in accordance with my invention, the structure being shown in the open condition; Fig. 2, a broken plan view of the same, on an enlarged scale; Fig. 25 3, a vertical sectional view taken as indicated at line 3 of Fig. 2; and Fig. 4, a vertical sectional view taken as indicated at line 4 of Fig. 2, but showing the structure in folded or table form.

30 In the embodiment shown, the invention comprises a table-frame A equipped with a movable top A', which is so connected with the folding-bed as to be automatically raised in the operation of converting the 35 structure to bed form; a stationary bed-housing member B extending parallel with the rear side of the table and constituting a panel; a swinging bed-housing member or mounting C equipped with brackets C', 40 joined by pivots 1 to bearings carried by the end-standards of the table-frame; and a folding-bed D mounted on the swinging-housing section C. The table-frame may be of any approved construction. As shown, it 45 comprises end-standards 2 which are rigidly connected by the stationary panel B and also by members 3 and 4, which form with the upper portion of the panel B a box 5. The table-top A' is connected, by hinges 6, 50 with the upper edge of the member or rail 4.

The rear housing-section B, which, as stated, is stationary, is disposed some distance in front of the plane of the rear face

of the table, thus affording room for one to be seated comfortably at the table. 55

The housing-section C, when in the vertical position shown in Fig. 4, is disposed about the same distance from the plane of the front face of the table as is the section B from the rear face of the table, so that 60 room is afforded at the front side of the table to enable a person to be comfortably seated. Referring to the structure when in table form, the panel C is equipped near its upper portion with a box 7, corresponding 65 with the box 5. The box 7 is fitted with knobs 8, which afford feet adapted to support the outer end of the section C when it is in the lowered or horizontal position. The sections B and C afford rear and front 70 panels for the table, and may be made as ornamental as desired.

The brackets C' are rigidly secured, as shown in Fig. 4, to the inner surface of the lower corner-portions of the swinging-section C. When the panel C is in the horizontal position, the brackets C' are disposed above the panel, as shown in Fig. 3. The brackets are secured to the panel by screws 9. The pivots, or studs 1, are secured to the 80 upper ends of the members C' in the manner shown in Fig. 4. The studs 1 are provided at their outer ends with heads, and the studs are demountably received in slotted clips, or bearings, 10 which are securely fastened to 85 the inner surfaces of the end-frames 2 of the table, as will be clearly understood from Figs. 2 and 3. Thus, the end-standards of the main-frame are further connected through the medium of the headed studs, 90 the brackets C', and the swinging panel C. It will be noted from Fig. 3, that the pivots 1 are disposed some distance in front of the rear or lower end of the panel C, so that the swinging panel is partially counter-balanced. The brackets C' are joined, by links 11, to lugs 12, with which the lower surface 95 of the table-top is equipped. The lower ends of the links 11 are provided with slots 13 which engage studs 14 with which the 100 brackets C' are equipped, thus providing a lost-motion connection.

The folding-bed D, referring to the structure in the opening condition, comprises a rear main-section 15; a rear spacing-section 105 16; an intermediate main-section 17; a front

spacing-section 18; and a front main-section 19. These sections are joined together in the usual way, so as to give rigidity in the extended position, and so that the sections 5 will be successively folded on each other by the engagement of suitable shoulders, in the folding operation. The rear portion of the rear section 15 is connected, by links 20, to the rear portion of the swinging-panel C. 10 The rear spacing-section 16 is mounted on pivots 21 carried by the arms, or standards, 22 of a truss 23 mounted on the box 7 at the outer or upper end of the panel C.

The intermediate main-section 17 is 15 equipped with folding legs 23^a joined by links 24 to the rear spacing-section 16. The front main-section 19 is equipped with folding legs 25 which are connected, by links 26, to the front spacing-section 18. 20 The legs 25 are equipped with locking arms 27 provided with notches 28 adapted to engage locking studs 29 with which the main intermediate section 17 is equipped. Thus, in the folding operation, the section 19 may 25 be brought to a superposed position with relation to the section 17 and locked to the section 17, after which the section 17 may be folded with relation to the section 15, in which position the section 19 will 30 occupy an intermediate position, the main-sections all being spaced, however, a sufficient distance apart to accommodate the bedding. When the bed is folded so as to occupy a position above the swinging housing-section C, the housing-section C may be 35 swung about the pivots 1, thereby bringing the housing-section C to a standing position. In this operation, the table-top will be lowered by the links 11, and the folded 40 bed will be housed and entirely hidden from view between the stationary housing-section and the swinging housing-section and beneath the table-top.

To convert the structure from table-form 45 to bed-form, the housing-section C is swung forwardly and downwardly about the pivots 1, in which operation the table-top is automatically raised by the links 11, after which the folded bed may be unfolded in the usual 50 manner.

The structure described is very simple, provides a thoroughly comfortable bed when in the open condition, and provides a substantial table of pleasing appearance when 55 the structure is in the folded condition.

The foregoing detailed description has been given for clearness of understanding only, and no unnecessary limitation should be understood therefrom.

60 What I regard as new and desire to secure by Letters Patent is—

1. The combination with a table having a movable top, of a bed-housing disposed beneath said top and having a downwardly 65 swinging-section, a folding-bed carried by

said swinging-section and comprising a plurality of foldably related bed-sections and connections between the swinging housing-section and table-top, serving to automatically 70 actuate the table-top.

2. The combination with a table having a frame and a movable top, of a bed-housing disposed beneath said top and having a swinging-section connected with the table-frame some distance above the lower end of the swinging-section, links connecting the lower end of the swinging-section with the table-top, and a folding-bed carried by said swinging-section and comprising a plurality 75 of foldably related bed-sections.

3. The combination with a table having a movable top, of a bed-housing disposed beneath said top and comprising a stationary rear panel and a swinging front panel, and a folding-bed mounted directly on the inner 80 surface of said swinging panel and comprising a plurality of foldably related bed-sections.

4. The combination with a table having a frame and a movable top, of a bed-housing disposed beneath said top and having a swinging-section connected above its lower end with the ends of the table-frame, and a folding-bed comprising a rear main-section movably mounted on the swinging housing-section, a rear spacing section pivotally mounted on the upper portion of the swinging housing-section and connected with the rear main-section, another main-section pivotally connected with said spacing section, 90 and folding legs connected with said second-named main section.

5. The combination with a table provided with a top, of a housing-section disposed beneath said top and adapted to swing from a standing position to a substantially horizontal position, and a folding-bed comprising a rear main-section movable on said swinging housing-section, a rear spacing-section pivotally mounted on the upper portion of said housing-section, an intermediate main-section pivotally connected with said spacing-section, folding legs connected with said intermediate main-section, an outer spacing-section foldably connected with the intermediate main-section, an outer main-section pivotally connected with the front spacing-section, and legs foldably connected with the outer main-section.

6. The combination with a table having a frame and a movable top, of a bed-housing disposed beneath said top and having a swinging section equipped at its lower portion with brackets, pivotal connections between the upper portion of said brackets and the end-portions of the table-frame, links connecting said bracket with the table-top, and a folded bed carried by said swinging section and comprising a plurality of foldably related bed-sections.

7. The combination with a table having a movable top, of a bed-housing disposed beneath said top and comprising a vertical rear panel and a vertical swinging front panel having its upper portion equipped with supporting means adapted to rest on the floor when the swinging panel is in the horizontal position, and a folding-bed mounted directly on the inner surface of said 10 swinging panel and comprising a plurality of foldably related bed-sections.

8. The combination with a table having a swinging top, of a bed-housing disposed be-

neath said top and comprising a stationary rear panel and a swinging front panel, the 15 front panel equipped at its upper portion with means adapted to rest on the floor, link-connections between the swinging panel and the table-top, and a folding-bed mounted directly on the inner surface of said swing- 20 ing panel and comprising a plurality of foldably related bed-sections.

PETER E. KROEHLER.
